UNITED STATES PATENT OFFICE.

JACOB EDWIN WOODS, OF DONORA, PENNSYLVANIA.

WINDOW-FIXTURE.

No. 807,101.

Specification of Letters Patent.

Patented Dec. 12, 1905.

Application filed June 10, 1905. Serial No. 264,627.

To all whom it may concern:

Be it known that I, JACOB EDWIN WOODS, a citizen of the United States of America, residing at Donora, in the county of Washington and State of Pennsylvania, have invented 5 certain new and useful Improvements in Window-Fixtures, of which the following is a specification, reference being had therein to the accompanying drawings.

This invention relates to certain new and useful improvements in window-fixtures; and the primary object of the invention is to provide novel and effective means for conveniently supporting both the shades and curtains from the same supporting structure attached to the window-frame.

Briefly described, the invention comprises supporting members which are attached to the window-frame and which are peculiarly 20 constructed to receive adjustable supporting-brackets for the shade-roller, the supporting members also having curtain-supporting brackets attached thereto. The supporting members may be attached to the 25 window-frame in any desired manner, as by screws or nails, and owing to their nature they may be used in lieu of the plinth-blocks of a window-frame.

In the accompanying drawings, Figure 1 30 is a perspective view of a portion of a window with my improved fixture thereon. Fig. 2 is a front elevation of one of my improved fixtures with the curtain-supporting bracket removed. Fig. 3 is a transverse vertical sectional view thereof. Fig. 4 is a detached view, in side elevation, of the curtain-supporting bracket; and Fig. 5 is a similar view of the shade-supporting bracket.

The supporting member for the curtain- 40 pole and for the shade-pole is made up of two plates 1 and 2, superposed one on the other, and which plates are adapted to be attached to the window-frame, as by screws or nails or any other suitable means. The plate 1, 45 which is the underneath plate, is provided near its lower edge with a groove 3, and the plate 2 is divided into two sections, the upper wider section having its lower edge overlying the groove 3 to some extent and the 50 lower narrower section of the support pro-

jecting upwardly and overlying the groove 3 to some extent. The space between the adjacent ends of these two sections of the plate 2, together with the groove 3, consequently form a substantially T-shaped groove, and this T-shaped groove receives a T-shaped head 4, formed on the inner end of the shade-supporting bracket 5. The shade-supporting bracket at one side of the window of course, as usual, will be formed with an opening to receive the pintle of the shade-roller, and the other shade-bracket will be formed with a notch, as is the usual construction for the two shade-brackets. All of this construction, however, is otherwise identical in 60 construction, each having a depending lug 6, provided with a threaded aperture to receive a set-screw 7, that takes into the lower strip of the plate 2 and firmly securing the shade-bracket in the adjusted position. A plate 2 70 is further provided with recesses or seats 8, in which is received the angular ends 9 of the curtain-supporting bracket 10, these angular ends being secured in the seats by screws, nails, or other suitable means.

By forming the plate 2 in two sections the manner of forming the T-shaped groove 3 is materially simplified and the cost of construction reduced to a minimum. The shade-brackets may be adjusted in the 80 groove of the supporting members and then secured in the adjusted position by the set-screws 7.

In the practice of the invention it will be noted that various changes may be made in 85 the details of construction without departing from the general spirit and scope of the invention.

What I claim, and desire to secure by Letters Patent, is—

1. A window fixture comprising a supporting member embodying two plates superposed one on the other, the outer plate being formed in two sections spaced from each other and overlying a groove formed in the 95 underneath plate, brackets adjustably mounted in said groove, set-screws passing through the brackets and engaging the outer plate and curtain-supporting brackets secured to the outer plate, substantially as described.

2. A window-fixture, comprising a supporting member embodying a plate having an undercut groove, and a shade-supporting bracket having a T-shaped head working in
5 said groove and having a depending lug and a set-screw passing through the lug of said bracket and engaging said plate.

In testimony whereof I affix my signature in the presence of two witnesses.

JACOB EDWIN WOODS.
